UNITED STATES PATENT OFFICE.

ALEXANDER E. TRAINOR AND ROBERT F. MORRIS, OF SUISUN CITY, CALIFORNIA.

AUTOMOBILE-LIFTING DEVICE.

1,334,509.

Specification of Letters Patent. Patented Mar. 23, 1920.

Application filed April 16, 1919. Serial No. 290,436.

To all whom it may concern:

Be it known that we, ALEXANDER E. TRAINOR and ROBERT F. MORRIS, both citizens of the United States, residing at Suisun City, in the county of Solano and State of California, have invented new and useful Improvements in Automobile-Lifting Devices, of which the following is a specification.

10 This invention particularly relates to an automobile lifting device.

It is the principal object of the present invention to provide a structure which will be decidedly simple in its design and operation and upon which automobiles may be placed and supported a considerable distance above the level of the floor, thereby eliminating the use of objectionable pits for the repair of the car while holding the car 20 in a position where it may be conveniently repaired or otherwise given attention.

The present invention contemplates the use of a rigid base structure upon which is pivotally mounted at a point intermediate 25 its ends, a runway adapted to be tilted to a horizontal plane, said runway being tilted by the weight of an automobile as it is transferred therewith by the operation of a windlass carried on the base structure.

30 The invention is illustrated, by way of example, in the accompanying drawings, in which—

Figure 1 is a view in side elevation, illustrating the complete device and further 35 showing it in dotted lines, as elevated.

Fig. 2 is a view in plan elevation for showing the invention and particularly disclosing the parallel runways thereof.

Fig. 3 is a view in vertical section, as seen 40 along the line 3—3 of Fig. 2 and discloses the construction of the base.

Fig. 4 is a view in vertical section, as seen on the line 4—4 of Fig. 2, disclosing the formation of the runways and the manner 45 in which they are supported.

Fig. 5 is an enlarged fragmentary view, illustrating the hinge connection for the trip members.

Fig. 6 is a view in end elevation and section as seen on the line 6—6 of Fig. 2, further disclosing the reinforcement of the base.

Fig. 7 is a view in section and elevation corresponding to Fig. 5, showing the foot member in its unfolded position.

Fig. 8 is a fragmentary view, illustrating

the manner in which the members are fastened together.

Fig. 9 is a fragmentary view, illustrating the manner in which the elements of the base are secured to each other.

Referring more particularly to the drawings, the present invention comprises a base structure 10 and a platform or runway 11. The base structure is here shown as formed 65 with vertical legs 12 which are secured to parallel side rails 13. These side rails are secured together by cross rails 14, as more particularly shown in Fig. 2. A set of reinforcing members 15 are secured to the legs and the side and cross rail, as shown in Figs. 1, 3, 4 and 6, thus holding the base structure in a rigid position upon a base floor 16, shown in Fig. 1. This design provides that the complete base, including the 70 floor 16, the various legs 12 and the horizontally extending rails will form a rigid structure at one end of which the runway 11 is mounted.

At a point substantially midway the ends 80 of the runway, a cross bar 18 is provided. This bar is fitted with a plurality of hinges 19, which are secured to the end cross member 14 of the base structure, and by this means the runway may be swung vertically 85 to move from an inclined position, as indicated by solid lines in Fig. 1, to a horizontally aligned position, as indicated by dotted lines in the same figure. The runway itself comprises two track members 19' and 20, 90 which are parallel to each other and are spaced a distance apart representing the width between the wheels of an ordinary automobile. The outer sides of these track members are provided with guard ledges 21 95 by which the wheels will be held upon the tracks and which will prevent accident, due to any cause whatsoever. Mounted at the outer or free end of the runway and supported therebeneath is a pair of legs 22,

which may swing downwardly to support the runway when in its position, as shown in dotted lines in Fig. 1. These legs may swing outwardly upon their hinges and will assume abutting positions against a 100 stop rail 23, which is fastened across from one track member 19' to the opposite one.

At the opposite end of the base member from the point to which the runway is hinged is provided a windlass 24. This 110 windlass is supported within suitable bearings 25, secured upon extensions of the side

walls 13 of the base. The windlass is here shown as provided with opposite winding cranks 26. It will be understood that instead of using the shaft as shown in the drawings, that it will be desirable at times to provide an enlarged winding drum and this might be done without interfering with the spirit of the present invention. The drum or shaft 24 is fitted with a cable 27. 10 This cable is intended to be fastened to the rear or front axle of the vehicle and to draw the vehicle along the runway to its position of support upon the base.

In operation of the present invention, the 15 automobile is placed with its front or rear wheel upon the lower inclined end of the runway 11. The cable 27 is then fastened to the end of the automobile and the windlass rotated. As the automobile is drawn up and 20 along the runway, as indicated in Fig. 1, the weight of the vehicle will be transferred past the center of the pivot of the runway, and it will thus cause the free end of the runway to swing upwardly in the direction 25 of the arrow *a*, as indicated in Fig. 1 and then cause the runway to assume a position in a horizontal plane. This will hold an automobile directly over the base and will rigidly support it so that work may be done 30 around or under the machine without difficulty.

It will thus be seen that the device here disclosed, while decidedly simple in its construction and design, at the same time provides suitable means which may be conveniently operated for placing an automobile in a position where it may be easily repaired. This will eliminate the use of pits 35 within which gas accumulates and which are otherwise dangerous, thus placing the automobile in full view from all sides and beneath and allow complete ventilation to be provided the workmen as they proceed with the repair work.

40 While we have shown the preferred form of our invention as it is now known to us,

it will be understood that various changes in the construction, combination, arrangement of parts may be made by one skilled in the art, without departing from the spirit 50 of the invention as claimed.

Having thus described our invention, what we claim and desire to secure by Letters Patent is—

1. A device to transfer vehicles from one 55 elevation to another, including a rectangular table with supporting legs and braces, a supplemental table of substantially double the length of the main table and having wheel tracks and guards and a transverse central 60 cross bar, hinges by which the cross bar is tiltably connected with the posts of the supporting table at one end, legs hinged beneath and near the outer end of the tilttable, and a stop rail transversely of the table 65 against which the legs abut when unfolded to maintain the tilttable table horizontal.

2. A device to transfer vehicles from one elevation to another including a rectangular supporting frame having legs and braces, a 70 pair of continuous trackways of substantially twice the length of the main frame and secured in parallel relation to each other, hinge means for securing the trackways to one end of the main frame, a windlass mechanism secured to the opposite end of the main frame and adapted to be used in drawing a vehicle upwardly along the normally inclined trackways, and legs normally folded beneath the outer end of the trackways and 80 adapted to assume vertical positions therebeneath when a vehicle has been drawn along the trackways to a position over the main frame.

In testimony whereof we have hereunto 85 set our hands in the presence of two subscribing witnesses.

ALEXANDER E. TRAINOR.
ROBERT F. MORRIS.
